UNITED STATES PATENT OFFICE

169,464

MANNEQUIN

Millard F. Wells, Bellwood, Ill., assignor to W. L. Stensgaard and Associates, Inc., a corporation of Illinois

Application January 19, 1953, Serial No. 23,174

Term of patent 14 years

(Cl. D80—8)

To all whom it may concern:

Be it known that I, Millard F. Wells, a citizen of the United States, residing in Bellwood, in the county of Cook and State of Illinois, have invented a new, original, and ornamental Design for a Mannequin, of which the following is a specification, reference being had to the accompanying drawing, forming part thereof.

I claim:

The ornamental design for a mannequin, as shown.

MILLARD F. WELLS.
